UNITED STATES PATENT OFFICE.

MARY SETINA, OF MILWAUKEE, WISCONSIN.

CAP.

1,323,108.

Specification of Letters Patent. Patented Nov. 25, 1919.

Application filed September 4, 1918. Serial No. 252,562.

To all whom it may concern:

Be it known that I, MARY SETINA, a citizen of the United States, and resident of Milwaukee, in the county of Milwaukee and

5 State of Wisconsin, have invented new and useful Improvements in Caps, of which the following is a description, reference being had to the accompanying drawings, which are a part of this specification.

10 The invention relates to caps and more particularly to a cap which unlike others is made of straw and which is fully described and explained in the specification and shown in the accompanying drawings in

15 which:

Figure 1 is a perspective view of the cap embodying the invention;

Fig. 2 is a vertical sectional view of the cap on the line 2—2 of Fig. 3; and

20 Fig. 3 is a section taken on the line 3—3 of Fig. 2.

In the drawings the numeral 4 designates generally the body of the cap and 5 the vizor.

25 The body of the cap consists of a substantially flat top portion 6, curved sides 7 and circular crown 8. The sides 7 are curved outwardly and then downwardly and inwardly to the crown which is of less diameter than the upper portion of the cap. The cap is made of Milan straw or may be made of other flexible straw which is woven or formed to produce the body above described. In the present instance the Milan

straw which generally comes in long strands 35 is wound from the center 9 and sewed in successive layers to form the body of the cap.

The vizor 5 is made of the same material so as to form one piece which is attached to 40 the front portion of the crown on the inner side 10 and the usual sweat band 11 is then secured to the interior of the crown.

The portion of the curved sides 7, adjacent the vizor 5, is preferably extended 45 beyond the crown 8 a greater distance than the remaining portion of the sides, whereby the outer periphery of the same will be disposed near that of the outer edge of the vizor, as best shown in Figs. 1 and 2.

50 The cap thus formed is of pleasing appearance, and is light and comfortable to the wearer.

What I claim as my invention is:

A flexible cap comprising a body of pliable straw including a substantially flat top portion, a circular crown portion, and side portions curved inwardly from the top to the crown portion, and a flexible vizor of straw secured to the crown portion, the sides 55 of the body being projected beyond the crown portion and the portion of the sides adjacent the vizor being projected beyond the crown portion a greater distance than the remainder of the sides.

60 In testimony whereof, I affix my signature.

MARY SETINA.
